AUTOMOTIVE VEHICLE HOOD ORNAMENT

Arthur Ross, Detroit, Mich., assignor to General
Motors Corporation, Detroit, Mich., a corpora-
tion of Delaware

Application November 12, 1949, Serial No. 5,999

Term of patent 7 years

(Cl. D14—18)

To all whom it may concern:

Be it known that I, Arthur Ross, a citizen of the United States, being a resident of Detroit, State of Michigan, have invented a new, original, and ornamental Design for an Automotive Vehicle Hood Ornament, of which the following is a specification, reference being made to the accompanying drawing, forming a part thereof.

In the drawing:

Figure 1 is a plan view of an automotive vehicle hood ornament, showing my new design.

Figure 2 is a side elevational view thereof.

Figure 3 is an end elevational view thereof.

Figures 4, 5, 6, 7 and 8 are sectional views taken substantially on lines 4—4, 5—5, 6—6, 7—7 and 8—8, respectively, of Figure 1.

Figure 9 is a sectional view taken substantially on line 9—9 of Figure 2.

I claim:

The ornamental design for an automotive vehicle hood ornament, substantially as shown.
ARTHUR ROSS.
